US00D925489S

(12) **United States Design Patent** (10) **Patent No.:** **US D925,489 S**
Brunner et al. (45) **Date of Patent:** **** Jul. 20, 2021**

(54) **AUDIO LISTENING SYSTEM**

(71) Applicant: **Apple Inc.**, Cupertino, CA (US)

(72) Inventors: **Robert Brunner**, Glen Ellen, CA (US);
Rhys Bonahoom, Burlingame, CA (US); **Gregoire Vandenbussche**, San Francisco, CA (US); **Nivay Anandarajah**, San Francisco, CA (US); **Christopher Fruhauf**, San Anselmo, CA (US)

(73) Assignee: **Apple Inc.**, Cupertino, CA (US)

(**) Term: **15 Years**

(21) Appl. No.: **29/739,419**

(22) Filed: **Jun. 25, 2020**

Related U.S. Application Data

(63) Continuation of application No. 29/682,934, filed on Mar. 8, 2019, now Pat. No. Des. 889,432, which is a continuation of application No. 29/608,560, filed on Jun. 22, 2017, now Pat. No. Des. 843,345, which is a continuation of application No. 29/559,678, filed on Mar. 30, 2016, now Pat. No. Des. 791,733, which is a continuation of application No. 29/527,765, filed on May 21, 2015, now Pat. No. Des. 760,687, which is a continuation of application No. 29/490,508, filed on May 9, 2014, now Pat. No. Des. 738,350, and a continuation of application No. 29/490,507, filed on May 9, 2014, now Pat. No. Des. 732,000, which is a continuation-in-part of application No. 29/489,127, filed on Apr. 25, 2014, now Pat. No. Des. 731,457, and a continuation of application No. 29/489,127, filed on Apr. 25, 2014, now Pat. No. Des. 731,457, said application No. 29/490,508 is a continuation-in-part of application No. 29/489,127, filed on Apr. 25, 2014, now Pat. No. Des. 731,457.

(57) **CLAIM**

The ornamental design for an audio listening system, as shown and described.

DESCRIPTION

FIG. 1 is a perspective view of an audio listening system showing the claimed design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines in the figures show portions of the audio listening system that form no part of the claimed design.

1 Claim, 4 Drawing Sheets
